UNITED STATES PATENT OFFICE.

GEORGE S. HOLLISTER, OF BURKBURNETT, TEXAS, ASSIGNOR TO JAMES B. PAULEY,
TRUSTEE, OF CHICAGO, ILLINOIS.

OIL-WELL HEATER.

Application filed July 13, 1922. Serial No. 574,649.

To all whom it may concern:

Be it known that I, GEORGE S. HOLLISTER, a citizen of the United States of America, and a resident of Burkburnett, county of 5 Wichita, and State of Texas, have invented certain new and useful Improvements in Oil-Well Heaters, of which the following is a specification.

My invention relates to apparatus for 10 heating oil wells so as to increase the flow of oil therefrom, and has for its object improvements in such devices.

A typical oil well may be represented as 15 a hole about six inches in diameter and extending down about two thousand feet, more or less. At about this depth is found a stratum of rock, as limestone, some five or ten feet thick. Beneath this limestone is usually a stratum of sand from which is 20 obtained a flow of gas, and hence is called "gas sand." Under the gas sand is found forty or fifty feet of oil sand resting on a rock foundation. The hole is drilled down thru the oil sand and some eight or ten 25 feet into the rock foundation. That part of the hole which is above the sandstone is lined with pipe or tubing, but that which is below is not lined. The hole in the rock below the sand is in the nature of a trap 30 or catch basin to receive sand caving in above.

Crude oil has a paraffin or an asphaltum 35 base, and contains several volatile hydrocarbons. It is drawn from the well by a pumping operation which commonly places the oil sand under a comparatively high degree of vacuum. Under these conditions the volatile oils change to gas, and in so doing they absorb heat and consequently 40 cool the oil bearing sand or rock in the immediate neighborhood of the well. This cooling results in solidifying the paraffin or asphaltum in the pores in the sand thru which the oil must flow to be pumped. This 45 process gradually seals the walls of the well and stops the flow of oil. The remedy is to melt these solid deposits by the application of heat, and to pump them out when melted.

The best means for accomplishing this 50 result is to use an electric heater, but there are a good many difficulties connected with this operation and it is the object of the present construction to overcome these difficulties. The hole to be heated is less than

six inches in diameter, is frequently forty feet or more in length, and is down some two thousand feet below the surface of the earth. The heater must be immersed in the oil in the well and that oil must serve as a circulating 60 medium to convey heat from the heater to the walls of the well. An electric heater has a high temperature at the heating element, and such high temperature has a tendency 65 to form carbon deposits from the oil. The device must be so constructed that such deposits will not short circuit the current flowing thru the heating element.

To heat the walls of a hole forty feet or 70 more long, the heater which is immersed in the oil of the well should be twenty feet or more in length. Such heaters are subject to two forms of peril, both of which have been very destructive to the heaters heretofore used. One of these is that the oil level 75 in the well will sometimes subside and leave the upper end of the heater surrounded by gas in a confined space. Under such circumstances the ordinary heaters burn out at the upper end because there is no circulation 80 of oil to carry away the heat generated in the heating element. Another menace which frequently destroys the heaters heretofore made is the caving in of the walls 85 of the hole and the burying of the lower part of the heater in sand. In such cases the lower part becomes burned out and destroyed. The present heater is designed to overcome the dangers arising from both of these conditions, neither one of which can 90 be avoided.

In the accompanying drawings—

Fig. 1 is a section of the lower part of an oil well, the present device being shown in elevation;

Fig. 2 is an enlarged elevation of the upper part of the device, the shell of which is shown in section;

Fig. 3 is a still more enlarged section of part of the devices shown in Fig. 2;

Fig. 4 is a section on the same scale as Fig. 3 of the lower part of the device shown in Fig. 1; and

Figs. 5, 6, 7 and 8 are sections on correspondingly marked lines of Figs. 3 and 4.

The well is provided with a casing 11 which extends down to the limestone stratum which overlies the gas and oil bearing sand. The heater is enclosed in a shell formed of parts 12 and 13 which are connected to 110

gether by a coupling 14. These parts are suspended in the well by a wire rope 15, in the interior of which are the insulated wires which carry the electric current for operating the heater.

The upper end of the shell section 12 is reduced in diameter as shown at 16 and on this is a coupling 17 and pipe 18 which extends upward to a point above that at which 10 the oil in the well is likely to reach when the device is in operation. The rope 15 runs thru this pipe, and on the upper end of the pipe is a stuffing box 49 designed to prevent any quantity of water getting into the section 12 of the shell.

The upper end of the coupling 14 is reduced in diameter, and the entire coupling is bored out for the reception of pipe 19, on the lower end of which is a cap 20. The 20 upper end of coupling 14 is counterbored to receive the gland 21 of a stuffing box for pipe 19, which pipe is screwed into said gland. The gland 21 is held down by a cap 22 which is screwed on the outside of the 25 upper end of coupling 14. Screwed upon the cap 22 is a short piece of pipe 23, and on the upper end of this pipe is a block 24 which is bored out to form a second stuffing box having a gland 25 and cap 26.

At a point near the neck 16, the wire rope 15 is bound by wire 27 wrapped around it, and the wires of the rope are unwound to form strands 28 which extend downward and thru holes 29 in lugs 30 on coupling 14.

The core 31 of the rope which is left when these strands are unwound carries the insulated wires 32 and 33 and is the body which is packed against moisture by the upper stuffing box 24-26.

The cap 22 has its upper end closed by a plate 34, thru which plate are small holes for the passage of insulated wires 35 and 36, which extend down to heating elements below. Above plate 34 these wires are spread 45 apart and have secured thereon metallic connections 37 and 38 which serve to form separable connections to the wires 32 and 33. The space within the tube 23 and around the connections 37 and 38 is filled with 50 sheets of mica 51 which are bored out to receive said connections.

The wire 36 is connected thru bridge 37 with the terminals 38 of heating units 39, and wire 35 is connected thru bridge 40 with terminals 41 of two other heating units of the same kind. At the lower ends these heating units are connected together by bridges 42 and 43, the corresponding terminals of the heating units being indicated by 38^a and 41^a. These heating units may be of any desired type, but those illustrated in the drawings are of the kind described in patent to Abbott, No. 1,367,341, issued February 1, 1921.

The heating units 39 are each inclosed in

a metal tube 44, and the ends of these tubes are secured firmly in blocks 45 and 46 as shown in Fig. 4. Secured upon the block 45 in a liquid tight manner is the cap 20, and similarly secured to the block 46 is a cap 47. As constructed, the heating units and the caps protecting their electrical terminals are suspended by pipe 19 from the gland 21 in the coupling 14, and this coupling in turn is suspended by strands 28 of rope 15. The 75 shell 13 is carried on the coupling 14 and has its lower end closed by a plug 48.

Owing to the great length of the device as compared to its diameter, the drawings show the parts broken off. For the purposes of a 80 better understanding it is desirable to give some of the dimensions found useful, tho it should be understood that these dimensions may be varied as circumstances may require. The shell 13 will ordinarily be 85 from four and one-half to five inches in diameter. The distance between blocks 45 and 46 may conveniently be from twelve to sixteen feet, and the distance from the cap 20 to the coupling 14 may be some four or five 90 feet. The coupling 14 and the plug 48 make liquid tight joints at the two ends of the shell section 13.

Assuming dimensions such as those given, the shell 13 is filled up to some point between cap 20 and coupling 14 with some liquid, as kerosene, which is a non-conductor of electricity. The space above the liquid is an air space, which it is desirable should be two or three feet in length. With the device in this condition it is lowered into the well to a point about mid-way of the oil bearing sand or rock, and should be entirely immersed in the oil in the well. If the electric current be then turned on, the center or axial part of the long column of kerosene will be heated by the heating units, and the outside of this column will be cooled by contact of the shell 13 with the oil in the well. Under these conditions there will be set up 100 a circulation of the kerosene, which circulation will consist of a central upward flow along the heating units and an annular downward flow along the inner wall of shell 13. This will convey heat from the heating 115 units to the shell 13 by convection as distinguished from radiation, and from here it will be radiated thru the wall of shell 13 to the oil in the well. From this point the heat will be conveyed partly by radiation, and partly by convection, to the sand or rock which has its pores choked with 120 sealed paraffin.

If we assume that while this heating process is going on, the walls of the well 125 cave in and bury some four or five feet of the lower end of shell 13 in a solid bed of sand, then all convection at this surface will cease and heat be conveyed to the sand solely by radiation. As sand is a compara- 130

tively poor conductor of heat, this lower buried portion of the device will become overheated unless some means is provided to carry away the heat and thus prevent such 5 overheating. The circulating kerosene is such means. The same is true in case the oil in the well should subside and leave the upper portion of the shell 13 surrounded by nothing but the gas in the well. The circulation 10 of the kerosene will carry the heat from the overheated portions to the portions of shell 13 which are in contact with oil in the well.

In oil wells there is always a certain 15 amount of moisture, much of which condenses on the walls of the casing 11 and runs down into the well. Some of it also condenses on the rope 15 and, if not prevented, will run into the apparatus and 20 short circuit the electric connections. The stuffing box 49 is designed to prevent this, but it is not possible to make a perfectly tight stuffing box for a wire rope. Some water will get by the stuffing box 49. The 25 most of the water thus getting by this stuffing box will run down the inside wall of the pipe 18 and the inside wall of shell section 12 to the coupling 14. By an inspection of Figs. 2 and 3 it will be seen that the 30 space inside section 12 and above coupling forms a trap 50 into which water may accumulate until it rises up to the top of cap 26 before it can find entrance to the electrical connection. Of the water which runs 35 down the rope 15, the greater part will follow the strands 28 into the same trap. Of the water which reaches the core 31 and follows down that core, a considerable quantity 40 will be deflected by the conical top to the cap 26 and will flow into the same trap.

These various precautions are designed to 45 prevent water from reaching the electrical connection, but in spite of all precautions some water will get by in the long run. Such water will flow down the core 31 to the mica sheets 51, and by capillarity will cause a short circuit between the terminals 50 of wires 32 and 33 at the place where they connect with the connections 37 and 38. A short circuit at this point will cause much less damage than would be caused by water running down the wires 35 and 36 and causing a short circuit at the heating units.

The various devices involving the stuffing 55 boxes and drainage into the trap 50 will ordinarily prevent water getting to the electrical heating units. The mica packing 51 and the electrical connections at 37 and 38 constitute a safety device to protect the heating units in case the other devices should fail.

Heat is conveyed to the oil in the well, 60 from the exterior of the shell 13. The heating units are enclosed in metal tubes 44 which are immersed in a circulating medium

contained within the shell 13. The quantity of circulating medium is sufficient to completely submerge all parts directly heated by the heating units. It will be noticed that the circulating medium is not directly in 70 contact with the heating units but is heated indirectly thru the tubes 44, blocks 45 and 46, and caps 20 and 47. It will also be noted that the oil in the well is not heated directly by the parts just enumerated, but indirectly 75 thru the circulating medium and the shell 13. This process of indirect heating eliminates the formation of carbon deposits which, in ordinary practice, have been found to occur and cause trouble at numerous and unexpected places and in numerous and unexpected ways.

What I claim is:

1. In a device of the class described, a shell composed of two sections of tubular 85 form, an interior coupling connecting the sections and having an opening therethru, a pipe supported by the upper end of the coupling and extending downward thru the opening therein, a heating device located in 90 the lower section of said shell and supported by said pipe, and electrical connections extending downward thru said pipe to said heating device.

2. In a device of the class described, a shell composed of two sections, a coupling connecting said sections, a heating device located in the lower section and supported by 95 said coupling, electrical connections extending from the upper section thru an opening 100 in said coupling to the heating device, a circulating fluid partly filling the lower section and submerging the heating device, and means for protecting the electrical connections from contact with the circulating 105 fluid.

3. In a device of the class described, a shell composed of two sections, a coupling connecting the sections, a wire rope extending into the upper section, said rope having 110 its exterior wires separated from the core thereof and attached to the coupling for supporting the device, a heating device located in the lower section and suspended from the coupling, and electrical connections 115 extending from the core of the rope thru said coupling to said heating device.

4. In an oil well heater, a shell composed of two sections, a coupling connecting the sections, devices mounted upon the coupling 120 and extending upward in the upper section, said devices being of less diameter than the interior of the shell so as to leave an annular space between the shell and the devices, a wire rope extending into the upper section 125 of the shell and serving to support the apparatus, and electrical connections extending from the core of the rope thru said devices and said coupling to the lower section, said parts being so constructed that moisture con- 130

densing on said rope and running down the same will be conveyed to said annular space as a trap for receiving it.

5. In an oil well heater, a shell containing an electrical heating element, a wire rope by which the shell is supported, conducting wires located in the core of the rope and extending to the heating element, and a trap formed in the upper part of the shell and arranged to receive and retain water flowing down the rope.

6. In a device of the class described, a shell having an electric heating element in the lower portion thereof and a water trap in the upper portion, and a wire rope by which the shell is supported, the strands of said rope being so arranged that water running down said rope will be conveyed by said strands to said trap.

20 7. In a device of the class described, a shell having a water trap in the upper portion thereof, a wire rope by which the shell is supported, and a pipe extending upward from the shell and serving to protect said rope, said parts being so arranged that upon moisture entering the pipe and flowing down the interior wall of the pipe and down the exterior of the rope will be conveyed from both places to said trap.

25 8. In a device of the class described, a

shell, an electric heating element therein, a rope by which the device is suspended, an electric circuit for the heating element, retarding devices for preventing water from getting into the shell and being conveyed toward the heating element, and a safety device located between the retarding devices and the heating element and serving to short circuit the current flowing to the heating element in case water gets past the retarding devices.

30 9. In a device of the class described, the combination with a heating device, an electric circuit therefor, and means for normally preventing water from gaining entrance to the channel leading to the heating device, of a safety device located in such channel and serving to short circuit the heating device by any water which may get past the means for normally preventing such entrance.

35 10. In a device of the class described, the combination with a heating unit, an electric circuit therefor, and means for normally preventing water from gaining entrance to the channel leading to the heating unit, of electrical connections in said circuit and located in said channel, and a strata of insulating material such as mica filling such channel around said connections.

50 GEORGE S. HOLLISTER.
